UNITED STATES PATENT OFFICE.

CLAWSON DAVIS, OF ANN ARBOR, MICHIGAN, ASSIGNOR OF ONE-HALF TO C. J. SEY-
FRIED, OF MORENCI, MICHIGAN.

AIR-HEATING OIL STOVE.

Application filed September 20, 1926. Serial No. 136,596.

This invention relates to stoves, particularly those intended for heating air, and has for its object the provision of a novel stove for heating air and utilizing oil as the fuel, means being provided within the device for generating the oil into a vapor or gas and supplying an admixture of air thereto so as to produce a hot blast-like flame which will pass over an air inlet and effectually heat the air so that it will be discharged at the top of the device.

An important object is to provide a novel arrangement of fuel reservoir, air inlet and other detailed features which will herein-
15 after appear.

Another object is to provide a device of this character an electric fan which may be removed if its use is not desired but which is intended to act like a regular fan in warm weather and when the stove itself is not in operation, though the fan is capable of use for the purpose of directing a stream of hot air horizontally into a room so that it may act to warm up a far corner.

25 An additional object is to provide a stove of this character which possesses various structural advantages and features in addition to those enumerated and such as will hereinafter appear during the course of the following description and such as will be pointed out.

An additional object is to provide a stove of this character which will be comparatively simple and inexpensive in manufacture, easy to use, positive in action, efficient and durable in service, and a general improvement in the art.

With the above and other objects and advantages in view, the invention consists in the details of construction and the arrangement and combination of parts to be herein-
40 after more fully described and claimed, and illustrated in the accompanying drawings, in which:

45 Figure 1 is a vertical longitudinal section taken through the stove.

Figure 2 is a horizontal section taken on the line 2—2 of Figure 1, and

50 Figure 3 is a horizontal section taken on the line 3—3 of Figure 1.

Referring more particularly to the drawings, I have shown the stove as comprising a cylindrical casing 10 to which is secured, in any desired manner, a base 11, the assembly
55 being preferably mounted upon legs 12.

Located within the bottom portion of the casing and supported, as for instance upon an inturned flange 13 at the lower edge thereof is a tank or reservoir 14 for oil indicated at 15. At the top of the cylindrical shell is a perforated plate structure 16 for the outlet of heated air. Located within the intermediate portion of the shell or casing and suitably secured thereto is a frusto-conical shell member 17 which leads into a vertical cylindrical conduit 18 above which is a horizontal conduit 20 from which leads a conduit 18^a having a flaring upper end 19 secured to the upper portion of the casing or shell 10. The air conduit 20 communicates with the conduit 18 through an opening 21 and with the conduit 18^a through an opening 21^a. The conduit 20 leads to a perforated area 22 on the shell or casing 10 and is shown as having an opening 23 located in front of an electric fan 24 which is mounted in the space between the conduit 18 and the casing 10 and which may be supplied with current by any desired means.

Extending vertically through the center of the reservoir or tank 14 but arranged in non-communicating relation therewith is an air conduit 25 which communicates with an opening 26 at the center of the bottom 11 so that when the burner mechanism, to be described, is in operation, fresh air will be drawn through the conduit and discharged into the air conduit 18, the upper end of the conduit member 25 being flared as indicated at 27 and terminating within the frusto conical shell member 17.

Carried by the air conduit 25 at a point above the top of the tank 14 is a bracket structure 28 which carries the burner devices, indicated generally by the numeral 29. Each of these burner devices is shown as comprising a cylindrical shell member 30 open at its top and preferably terminating just short of the frusto conical shell member 17. Extending laterally through each of the shell members 30 is a generator pipe 31 having a reflexly curved end 32 extending and discharging into the shell member 30 as clearly indicated in Figure 1. The member 31 leads from a valve device including a body or casing 33 into which leads an oil conducting pipe 34 extending down into the bottom portion of the reservoir tank 14. Also leading into the body or casing 33 is an air inlet pipe 35 which extends into and

communicates with the upper portion of the tank or reservoir 14. Any suitable rotary plug or other cutoff may be provided to form a part of the valve device and is of course mounted within the body 33 and provided with an operating handle 36. A priming cup 37 may be provided within each of the cylindrical members 30 for the purpose of starting the operation of the burner.

In the operation of the device, it will of course be apparent that the generators or burners may be started in operation by placing a small quantity of oil within the priming cups 37 and igniting it so as to effect heating of the members 31 through which the mixture of oil and air will pass. After these members 31 have become thoroughly heated it is of course apparent that the oil drawn therethrough will become vaporized. The air within the reservoir 14 and above the surface of the oil therein is drawn into the generators or burners through the pipe 35 and will mix with the oil vapor or gas so as to provide a very easily combustible mixture which will burn, the flame issuing out at the top of the members 30. Of course, after the priming action is accomplished, the burning takes place at the discharge ends of the curved pipe members 32, the flame playing upon the members 31 and maintaining them in a thoroughly heated condition at all times. Furthermore, the provision or production of such a flame will cause a suction through the pipes 34 and 35 so a constant supply of oil and air will be brought to the burners or generators.

The flame issuing from the generators or burners causes a suction effect through the air conduit 25 so that fresh air will be drawn in at the bottom of the stove and will be effectually heated upon contact with the flame. The air of course passes upwardly through the cylindrical conduits 18 and 18^a and out at the top of the shell or casing 10 through the perforated cover plate 16.

In case it is desired to direct a horizontally extending or traveling stream of heated air into the far corner of a room or the like, the fan 24 may be set in operation so as to produce a transverse air blast through the conduit member 20, this heated air issuing out through the perforated area 22 in the side of the casing or shell 10.

In summertime, when there is no heat required, the fan 24 may be operated simply for cooling purposes in a well known and obvious manner. It is really believed that the construction, operation and advantages will be readily apparent to one skilled in the art without further explanation, though it should of course be pointed out at this time that there must be a certain door arrangement provided so that access may be had to the interior of the stove for the purpose of

replenishing the fuel supply and making any necessary adjustment of the burner valves or replacement of any parts which become burned out or need repairing.

While I have shown and described the preferred embodiment of the invention, it should be understood that I reserve the right to make such changes in the form, construction and arrangement of parts as will not depart from the spirit of the invention or the scope of the subjoined claims.

Having thus described the invention, I claim:

1. In a stove of the character described, a casing, a frusto conical shell member located within the intermediate portion of the casing, a conduit extending to the upper end of the casing, the upper end of said conduit being flared, the top of the casing being perforated, a fuel reservoir located within the bottom of the casing, an air inlet conduit extending upwardly centrally through the fuel reservoir in non-communicating relation thereto and discharging into said frusto conical shell member, and oil burners mounted within the casing between the oil reservoir and said frusto conical shell member.

2. In a stove of the character described, a casing, a frusto conical shell member located within the intermediate portion of the casing, a conduit above the shell member and extending to the upper end of the casing, the upper end of said conduit being flared, the top of the casing being perforated, a fuel reservoir located within the bottom of the casing, an air inlet conduit extending upwardly centrally through the fuel reservoir in non-communicating relation thereto and discharging into said frusto conical shell member, and oil burners mounted within the casing between the oil reservoir and said frusto conical shell member, oil supply pipes leading from the bottom portion of the reservoir into the burners and air supply pipes leading from the top of the reservoir into the oil burners.

3. In a stove of the character described, a casing, a frusto conical shell member located within the intermediate portion of the casing, a conduit connected with and receiving from the shell member, a second conduit extending to the upper end of the casing, the upper end of said second named conduit being flared, the top of the casing being perforated, a fuel reservoir located within the bottom of the casing, an air inlet conduit extending upwardly centrally through the fuel reservoir in non-communicating relation thereto and discharging into said frusto conical shell member and oil burners mounted within the casing between the oil reservoir and said frusto conical shell member, a laterally extending outlet conduit located between and communicating with said conduits and extending to a perforated area in

the side of the casing, and means for creating a lateral blast through said lateral conduit.

4. In a stove of the character described, 5 a casing, a frusto conical shell member located within the intermediate portion of the casing, a conduit connected with and receiving from the shell member, a second conduit extending to the upper end of the casing, the 10 upper end of said second conduit being flared, the top of the casing being perforated, a fuel reservoir located within the bottom of the casing, an air inlet conduit extending upwardly centrally through the fuel 15 reservoir in non-communicating relation thereto and discharging into said frusto

conical shell member, oil burners mounted within the casing between the oil reservoir and said frusto conical shell member, a laterally extending outlet conduit communicating with said first and second named conduits, and extending to a perforated area in the side of the casing, and means for creating a lateral blast through said lateral conduit, comprising an electric fan mounted 20 within the casing at one side of the conduit, the conduit having an opening therein opposite the fan and diametrically opposite the lateral conduit.

In testimony whereof I affix my signature.

CLAWSON DAVIS.
